HYDRAULIC TIMING APPARATUS

Maurice S. Hayes, 22142 Thelma St., Hayward, Calif.

Filed Aug. 2, 1961, Ser. No. 128,840

10 Claims. (Cl. 188—97)

This invention relates generally to devices for denoting periods of time, and more particularly is directed towards a hydraulic system which mechanically indicates a predetermined time interval.

In operating various mechanical apparatus, control systems, and the like, it is often necessary to maintain a particular element of the apparatus or system in a prescribed position for a given period of time. For example, a fluid flow system may require that a particular valve be opened and maintained in an open position for a time interval, and then be closed. Similar requirements are commonly encountered in other apparatus wherein the timing of various mechanical operations is important.

It is accordingly a primary object of the present invention to provide a novel and improved apparatus of the character described which mechanically indicates a predetermined time interval.

Another object of the invention is to provide a mechanical timing device which may be coupled into an apparatus or system to regulate the duration of various operations therein.

A further object of the invention is to provide apparatus of the character described which is readily adjusted to indicate time intervals of varied duration.

Still another object of the invention is to provide a mechanical timing apparatus having a relatively sharp cutoff characteristic to delineate the time interval.

An even further object of the invention is to provide apparatus of the character described which can be mechanically linked to a fluid valve or the like to regulate the duration for which it is open or closed.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

FIGURE 1 is a perspective view of a preferred embodiment of the invention;

FIGURE 2 is a cross sectional view in detail of the embodiment shown in FIGURE 1;

FIGURE 3 illustrates the invention during the setting operation, prior to the start of the time interval;

FIGURE 4 illustrates the invention during the time interval being indicated;

FIGURE 5 illustrates the invention at the end of the time interval; and

FIGURE 6 illustrates a system which may be coupled to the present invention to regulate the flow of fluid.

For a description of the invention in broad terms, reference is made to FIGURE 1 wherein is shown a hydraulic timer 11 having an actuating rod 12 extending outwardly therefrom. The timer 11 is set by withdrawing the rod 12, whereupon the rod remains substantially in the withdrawn position for a given period of time and then moves quickly back to its original position to indicate the end of the time interval. A knob 13 may be rotated to adjust the timer 11 to indicate intervals of different duration.

Looking now at FIGURE 2 for a more detailed description of the invention, the timer 11 is seen to include a main body member 14 having two elongated chambers 16 and 17, with three passageways 18, 19 and 21 respec-

2

tively communicating the intermediate portion 22 and the two end portions 23 and 24 of the chamber 16 with the corresponding intermediate portion 26 and end portions 27 and 28 of the chamber 17. In the preferred embodiment of the invention, as shown in the drawings, the main body member 14 includes two elongated hollow cylinders 29 and 31, which respectively define the chambers 16 and 17. Similarly, the body member 14 includes three connecting tubes 32, 33 and 34 which define the passageways 18, 19 and 21. It will be appreciated, however, that the chambers 16 and 17, and the passageways 18, 19 and 21 can also be readily provided as bores in a unitary block member, as well as by the illustrated several cylinders and connecting tubes.

It is next seen that a piston 36 is slidably disposed within the chamber 17, there being further provided means such as a tension spring 37 for urging the piston towards the end 38 of the chamber. Additional means, such as the actuating rod 12 which passes through the end 39 of the chamber 17 and connects to the piston, are provided in order to move the piston towards the end 39 against the force of the tension spring 37, this being accomplished simply by withdrawing the rod 12.

As regards now the chamber 16, there is provided therein a valve means 41 which is disposed between the end portion 23 and the intermediate portion 22 of the chamber 16. In greater detail, the valve means 41 includes a valve seat member 42, which is preferably of substantially annular shape and is disposed transversely within the chamber. A movable valve member 43, which is preferably of substantially spherical shape in the portion thereof confronting the seat member 42, is disposed within the chamber 16 between the intermediate portion 22 thereof and the seat member 42. Means for urging the valve member 43 towards the seat member 42 are then coupled to the valve member 43, such means being typified by the illustrated compression spring 44 connected between the valve member 43 and the end 46 of the cylinder 29.

Means are then provided for limiting the minimum opening between the valve member 43 and the seat member 42, as for example an elongated rod 47 which extends into the chamber 16 through the end 48 of the cylinder 29, and has its end 49 disposed in confronting relation with the valve member 43. The spacing between the valve member 43 and the seat member 42 is controlled by the axial position of the rod 47, which can be adjusted by adapting the rod 47 with an upper threaded portion 51 passing through a threaded bore 52 in the end 48 of the cylinder 29. Hence the size of the opening of the valving means 41 can be varied by simply turning the knob 13.

A fluid, for example, oil or the like, is then contained within the two chambers and three passageways, and of course communicates between them.

To describe the operation of the invention reference is now made to FIGURES 3, 4 and 5 wherein the instant timer 11 is shown during various stages of its operation. In order to set the timer, the actuating rod 12 is pulled upwardly, as designated by the arrow 53 in FIGURE 3, whereby the piston 36 is moved upwardly within the chamber. The motion of the piston causes the fluid above the piston to flow out of chamber 17 through the passageway 19 into the chamber 16, as indicated by the arrows 54. Similarly, the fluid in chamber 16 is free to pass therefrom past the valve means 41 and through the passageways 18 and 21 into the chamber 17, below the piston 36, as indicated by the arrows 56. It is important to note that little if any resistance or back pressure is encountered in raising the rod 12 in preparation for the timing cycle. In this connection, attention is directed to the fact that the effective cross sectional area of the pas-

sage in the valve means 41 and the area of the annular space between the ball 43 and the walls of the chamber 16 is at least equal to the cross sectional area of the piston 36. Consequently, upon raising of the rod, fluid is free to flow as above described. In the event the initial position of the ball 43 is adjusted to be close to the valve seat 42, thus suggesting a possible resistance to fluid flow, it will be appreciated that raising of rod 12 causes a positive pressure above the ball and a negative pressure below the ball, resulting in an opening of the space between the ball and the valve seat 42. Because the compression spring offers sufficiently small resistance, the valve member is easily moved downward and hence the actuating rod 12 may be moved upwardly with little difficulty.

When the piston 36 reaches its uppermost position, which is preferably limited to some place below the passageway 19, the timer is set. When the upward force on rod 12 is released, the tension spring begins to bear on the piston and the ensuing operation of the device is indicated in FIGURE 4, wherein the arrow 57 shows the downward motion of the piston under the force of the tension spring. It is important now to note that the speed of downward motion of the piston is controlled by the opening in the valve means 41. More particularly, as the piston is pulled down by the tension spring, the fluid under the piston is forced into the chamber 16 and upwardly through the valve means. Hence, the valve member is pushed upwardly until it encounters the end of the rod 47. Since the opening between the valve member and the valve seat is substantially restricted, the flow therethrough is necessarily retarded. Thus by varying the opening in the valve means, i.e., the spacing between the ball 43 and the valve seat, the rate of flow therethrough is varied, and ultimately the downward speed of the piston is controlled.

Once the top of the piston is substantially exposed to the passageway 18, the piston moves rapidly to complete the downward stroke, which motion is best illustrated in FIGURE 5. More specifically, after the piston passes the intermediate passageway 18, the valve means no longer controls the piston speed, and instead the pressure of the fluid under the piston is fed back through passageways 21 and 18 to bear on the top of the piston, as indicated by the arrows 58, whereby the tension spring quickly pulls down the piston.

The duration while the piston is moving relatively slowly between the passageways 19 and 18 comprises the time interval to be indicated by the instant invention. The rapid downward motion of the piston after it passes the passageway 18 indicates the end of the time interval, thereby providing a sharp cutoff characteristic to delineate the interval with a desirable degree of accuracy. By varying the axial position of the adjustment rod 47, it is clear that the duration of the time interval can also be varied.

As an example of one particular use of the instant invention, consider the system illustrated in FIGURE 6, wherein is shown a valve 59 having an intake conduit 61 and an outlet conduit 62. The valve is controlled by a lever arm 63, which in its upper position opens the valve and in its lower position closes the valve to thereby regulate the flow through the conduits 61 and 62. A relay 64 is coupled by a rod 66 to the lever arm 63, whereby the rod 66 is moved upwardly upon actuation of the relay 64 to open the valve 59, and the rod 66 moves downwardly when power to the relay is cut off, thereby closing the valve 59. Hence, a substantially instantaneous pulse of power to the relay will merely open the valve 59 for an instant. Now, by linking the rod 66 to the actuating rod 12 of the instant invention, the duration of time for which the valve 59 remains open can be predetermined. More specifically, a pulse of power to the relay will open the valve, and at the same time withdraw the rod 12 to set the instant timing device. When the power to the relay is cut off, the rod 66 does not simply

return to its lower position, but instead its downward motion is controlled by the motion of the rod 12. Hence, for a predetermined time interval the rod 66, and accordingly the lever arm 63, will move down very slowly, during which time interval the valve 59 remains open. At the end of the time interval the rod 12 moves down very quickly, to similarly allow the rod 66 and lever arm 63 to also complete their downward motion, whereby the valve 59 is closed with a sharp cutoff characteristic.

It will now be appreciated that a timing device may be provided by the invention which does not have the sharp cutoff characteristic described above, but instead exhibits a slow tapered cutoff characteristic which is suitable for many uses. More specifically, by eliminating the passageway 21, there will be no abrupt downward movement of the piston to indicate the end of the time interval. Instead, the piston will move slowly between the passageways 19 and 18 and merely come to rest substantially adjacent passageway 18. Note that the distance between passageways 19 and 18 governs the extent of movement of the actuating rod 12, and hence this distance may be enlarged to provide sufficient operative movement of the rod 12.

It will also be appreciated that with the apparatus above described, no limitations of specific orientation is required, since the device is capable of proper operation not only in the vertical position shown, but in a horizontal, inverted, or other desired disposition.

What is claimed is:

1. Timing apparatus of the character described including means defining spaced longitudinally extending first and second chambers, a first conduit interconnecting said chambers medially of the respective ends thereof, second and third conduits interconnecting said chambers at positions spaced from said first conduit on either side thereof and toward the corresponding ends of said chambers, said chambers and conduits being substantially filled with liquid, a piston mounted for longitudinal movement in said first chamber means for resiliently biasing said piston toward a first end of said chamber, means for moving said piston towards the second end of said chamber against said biasing means, and valve means mounted in said second chamber between said first conduit and one of said other conduits to control any fluid flow therethrough and being biased toward a closed position and operable to full open position by fluid pressure acting in opposition to said bias, the volume of the second chamber beyond the valve means being less than the volume of fluid displaced by the piston, said conduits, second chamber and valve means when open having a cross-sectional flow path for liquid movement between said chambers at least as large as the cross section of said first chamber and means for limiting movement of said valve in a closing direction.

2. Timing apparatus as described in claim 1 further characterized by said valve means including a valve seat member secured in said second chamber, a movable valve member disposed in said second chamber, means for resiliently urging said valve member towards said seat member, and means for limiting the minimum opening between said valve member and said seat member.

3. Hydraulic timing apparatus comprising, in combination means defining a pair of spaced longitudinally extending chambers, first means operatively connected to said chambers medially of the respective ends thereof and placing said chambers in communication with each other, second means operatively connected to said chambers intermediate said first means and the corresponding ends of said chambers and providing second communication between the chambers, third means operatively connected to said chambers intermediate said first means and the remaining corresponding ends of said chambers and providing third communication between the chambers, a piston mounted for longitudinal movement in one of said chambers, means for resiliently urging said piston towards the end of said one

chamber adjacent said second means, means for moving said piston towards the other end of said one chamber, adjacent said third means, valve means disposed in said other chamber intermediate said first and third means and adapted to restrict flow in said other chamber from said first means towards said third means.

4. Timing apparatus as described in claim 3 further characterized by said valve means including a valve seat member secured in said other chamber and disposed therein intermediate said first and second means, a movable valve member disposed in said other chamber intermediate said first means and said seat member, means for resiliently urging said valve member towards said seat member, and means for limiting the minimum opening between said valve member and said seat member.

5. Hydraulic timing apparatus comprising, in combination, a body member having two elongated chambers therein and three passageways respectively communicating the two end portions and intermediate portion of one chamber with the corresponding portions of the other chamber, a fluid contained in the chambers and passageways, a piston slidably disposed in a first of said chambers, means for resiliently urging said piston towards one end of said first chamber, means for moving said piston towards the other end of said first chamber, a valve seat member secured in the other chamber and disposed between the intermediate portion and the end portion thereof corresponding with said other end of said first chamber, a movable valve member disposed in said other chamber between its intermediate portion and said seat member and adapted to be moved towards said seat by said fluid when said piston is moved towards said one end of said first chamber, means for resiliently urging said valve member towards said seat member, and means for limiting the minimum opening between said valve member and said seat member.

6. Hydraulic timing apparatus comprising in combination, a body member having first and second elongated chambers therein, said body member further defining a first passageway communicating between said chambers from adjacent one end of said first chamber to adjacent one end of said second chamber, a second passageway communicating between said chambers from adjacent the other end of said first chamber to adjacent the other end of said second chamber, and a third passageway communicating between said chambers from intermediate the ends of said first chamber to intermediate the ends of said second chamber; a piston slidably disposed in said first chamber; means for resiliently urging said piston towards said one end of said first chamber; means for moving said piston towards said other end of said first chamber; a valve seat member secured in said second chamber and disposed intermediate said second and third passageways; a movable valve member disposed within said second chamber and disposed intermediate said seat member and said third passageway; means for resiliently urging said valve member towards said seat member; means for limiting the minimum opening between said valve member and said seat member; and a fluid contained in said chambers and passageways.

7. A hydraulic timing device comprising, in combination, a first elongated tubular member having both ends closed, a second elongated tubular member having both ends closed, a first connecting tube communicating between one end portion of said first tubular member and one end portion of said second tubular member, a second connecting tube communicating between the other end portion of said first tubular member and the other end portion of said second tubular member, a third connecting tube communicating between the intermediate portion of said first tubular member and the intermediate portion of said second tubular member, said connecting tubes and said second tubular member all having cross sectional areas at least as large as said first tubular member, a fluid contained in said tubular member and

connecting tubes, a piston slidably disposed in said tubular member, means for resiliently urging said piston toward one end of said first tubular member, means for moving said piston towards the other end of said first tubular member, a valve seat member secured within said second tubular member and disposed between the intermediate portion and the other end portion thereof, a movable valve member disposed within said second tubular member between the intermediate portion thereof and said seat member, means for resiliently urging said valve member towards said seat member, and stop means for limiting the minimum opening between said valve member and said seat member.

8. Hydraulic timing apparatus comprising, in combination, a body member having two elongated chambers therein and three passageways respectively communicating the two end portions and intermediate portion of one chamber with the corresponding portions of the other chamber, a fluid contained in the chambers and passageways, a piston slidably disposed in one chamber, means for urging said piston towards one end of said one chamber, means for moving said piston towards the other end of said one chamber, an annular valve seat member secured transversely in the other chamber and disposed therein between the intermediate portion and one end portion thereof, said passageways and the opening in said seat member all having cross sectional areas at least as large as said one chamber, a movable valve member disposed in said other chamber between the intermediate portion thereof and said seat member, means for urging said valve member towards said seat member, and means for limiting the minimum opening between said spherical valve member and said annular seat member.

9. A hydraulic timing device comprising, in combination, a first elongated hollow cylinder having both ends closed, a second elongated hollow cylinder having both ends closed, a first connecting tube communicating between one end portion of said first cylinder and one end portion of said second cylinder, a second connecting tube communicating between the other end portion of said first cylinder and the other end portion of said second cylinder, a third connecting tube communicating between the intermediate portion of said first cylinder and the intermediate portion of said second cylinder, a fluid contained in said cylinders and connecting tubes, a piston slidably disposed in said first cylinder, means for resiliently urging said piston towards said one end of said first cylinder, means for moving said piston towards said other end of said first cylinder, an annular valve seat member secured transversely within said second cylinder and disposed between the intermediate portion and said other end portion thereof, a movable substantially spherical valve member disposed within said second cylinder between the intermediate portion thereof and said seat member, means for resiliently urging said valve member towards said seat member, and an elongated rod extending into said second cylinder through its other end and adapted for adjustment to vary the axial position of said rod within said second cylinder.

10. Hydraulic timing apparatus comprising, in combination, a first elongated hollow cylinder having both ends closed, a second elongated hollow cylinder having both ends closed and disposed in substantially parallel spaced relationship with said first cylinder, a first connecting tube communicating between one end portion of said first cylinder and one end portion of said second cylinder, a second connecting tube communicating between the other end portion of said first cylinder and the other end portion of said second cylinder, a third connecting tube communicating between the intermediate portion of said first cylinder and the intermediate portion of said second cylinder, a fluid contained in said cylinders and connecting tubes, a piston slidably disposed in said first cylinder, a tension spring connected between said piston and said first cylinder adjacent one end thereof to urge said piston towards

said one end of said first cylinder, an actuating rod extending into said first cylinder through the other end thereof and connecting with said piston, an annular valve seat member secured transversely within said second cylinder and disposed between the intermediate portion and said other end portion thereof, a movable substantially spherical valve member disposed within said second cylinder between the intermediate portion thereof and said seat member, a compression spring disposed in said second cylinder and connected between said valve member and adjacent one end of said cylinder to urge said valve mem-

ber towards said seat member, and an elongated rod extending into said second cylinder through its other end and adapted for adjustment to vary its axial position within said second cylinder.
